SOLE-PRESSING LAST

Kurt Sandt, Pirmasens, Germany

Application November 11, 1936, Serial No. 110,368
In Germany November 9, 1933

13 Claims. (Cl. 12—123)

The smoothing of the soles of footwear is usually done, at the present day, in strong sole presses, which are preferably driven hydraulically for equalizing the thickness of the soles. In this a 5 somewhat specially shaped steel last is used as the smoothing last, which on account of the high pressure is as a rule formed in one piece with the last pillar or last carrier. For long sided footwear however, the steel last is separate from the 10 last pillar.

Now it is difficult to dimension the steel last so that on the one hand it can stand the relatively high stress and on the other hand enables the piece of work to be easily set up. The problem is especially difficult to solve with footwear having a closed vamp over the lacing or some other reduction in width in the instep, as for example in high legged boots, hunting and sporting boots with a high closure tongue and high 20 laced motoring boots, because on the one hand a division of the last and the last pillar cannot be avoided and on the other hand the toe of the shoe must be freely carried.

The invention relates to a last, which is more 25 particularly for use for pressing soles. The characteristic of the invention lies in the fact that the last pillar on its side directed towards the heel of the last is reduced towards the toe of the last so that after releasing the locking hooks and 30 on pushing the last towards the toe, the last pillar comes back with its projecting part in the region of the leg of the shoe and with its reduced part in the free space below the heel of the last and the last and the piece of work can be re- 35 moved upwards from the last pillar. Due to the projecting extension of the last pillar, the toe of the last which is otherwise freely carried receives a thorough support against the high pressure which results during pressing. In spite of this the 40 projecting extension does not interfere with the removal of the last from the pillar, because after releasing the catches the last can be so moved on the last pillar that its projecting heel end coincides with the last pillar and the projecting 45 extension of the pillar comes back into the last, whereby the piece of work with the smoothing last may be easily removed. The fore-mentioned extension corresponds to the wedge of a gripping last, but in the present case does not have to be 50 removed separately from the shoe in order to make possible removal from the last.

The device can be so arranged that the last is operated positively. With this object it may be connected to a rod or drive actuated by the 55 machine, which moves it automatically into the

pressure position when the last pillar is raised and pushes it towards the toe of the shoe when the last pillar sinks.

The object of the invention is illustrated by way of example in the drawings by various constructions:

Figure 1 shows a perspective view of a sole press.

Figure 2 shows a side view in part section through the complementary pieces which are in 10 the pressing position.

Figure 3 shows a similar view and the position of the parts while the piece of work is being changed.

Figure 4 shows a longitudinal section of the 15 inner form on the line III—III of Figure 2.

Figure 5 is a vertical sectional view, partly in elevation, showing the last in operative position on the last pillar and the last pillar elevated into operative relation with the upper form. 20

Figure 6 is a broken view of the last pillar and last of the construction shown in Figure 5, with the last moved to an inoperative position with respect to the pillar preparatory to removing the last and footwear from the last pillar. 25

Figure 7 is a section on the line VII—VII of Figure 5.

Figure 8 is a section on the line VIII—VIII of Figure 5.

Figure 9 is an elevation of the machine embodying the modified form shown in Figure 5. 30

Figure 10 is a view similar to Figure 6 showing the initial removal of the footwear.

Figure 11 is a view similar to Figure 10 showing the last in position to permit its separation 35 from the last pillar for the substitution of another last.

Figure 12 is a sectional view on the line XII—XII of Figure 9.

Figure 13 is an elevational view, partly in section, illustrating a modified form of machine.

Figure 14 is a section on the line XIV—XIV of Figure 13.

Figure 15 is a view showing the modified construction of Figure 13 with parts in position to 45 provide for the removal of the footwear and last from the last pillar.

On the counter member 1 of a sole-press a bush 2 is attached in which the spherical calotte 3 is suspended on a central anchor 4 (Figure 5). 50 In a swallowtailed guide in the spherical calotte 3 a sledge 5 is mounted to which the upper form 6 is screwed by bolts. The sledge 5 which is movable in the swallowtailed guide is centralized in respect to the spherical calotte 3 by means of 55

an adjustable stop 7 (Figure 5). The stop 7 is arranged on the sledge 5 that is screwed to the upper form, so that in changing the upper form, which can be done by merely drawing the sledge 5 out of its guide, the actual setting of the stop can be maintained. The position which the upper form takes up in relation to the calotte 3 is fixed by the action of a ball detent 8 (Figure 5) fixed in the guide sledge. In withdrawing the upper form 6 the ball detent 8 is temporarily pressed inwards against a compression spring 9.

As shown in Figure 2 the last 10, which is separate from the last pillar and which can be moved horizontally on it and fixed, grips over the last pillar 11 like a saddle. In the saddle like projections 13 of the last 10 eyes are provided in which the locking hooks 14 and 15 engage. These are arranged in groove-like apertures in the last pillar 11. They are pressed apart by a spring 16. The locking hooks 14 and 15 are prevented from falling out of the groove like apertures by means of plates 17 and 18 attached to the last pillar 11. On the locking hooks 14 and 15 buttons 19 and 20 are provided, which pass through the plates 17 and 18 and which can be moved inwards by pressing on the soft sides of the leg of the boot, in order to move the locking hooks 14 and 15 towards each other against the pressure of the spring 16 and undo the catches of the last. Setting up the boot 21 is done as follows: first the smoothing last 10 is inserted in the boot, then the boot 21 together with the smoothing last 10 is pushed over the last pillar 11 which stands on the support 22. The last and the last pillar are then in the position shown in Figure 3. Meanwhile, by pushing the boot 21 and the last 10 on the track 23 of the last pillar 11 the locking hooks 14 and 15 are brought into engagement with the openings in the saddle parts 13, so that the boot 21 comes into a position ready for working on it, as shown in Figure 2. In this position the last 10 has its heel end projecting over the last pillar. To remove it from the last the buttons 19 and 20 are pressed from the outside to move the locking hooks 14 and 15 inwards and undo the catches of the last. The last is then pushed relatively to the last pillar so that the last pillar goes back into the space below the heel of the last and takes up the position shown in Figure 3. The boot and last can then be removed from the last pillar and thereafter the last taken out of the boot.

In the construction illustrated in Figures 5 to 12 the machine piston 24, which can be raised or lowered, carries a last pillar 25 which is used to support the last 26. The footwear 21 which is put on the last is indicated in the drawings by chain dotted lines. On the side of the last pillar which is directed towards the heel there is arranged a vertically movable push rod 27, to the upper end of which is pivoted a link 28. The upper end of the link 28 is hook shaped and is hung on to a cross pin 29 of the last. The push rod 27 is provided with a stud 30 which works in a groove in the last pillar 25 (Figure 12) and limits the up and down movement of the push rod. At the lower end of the push rod 27 there is a lost motion connection 31, which works in conjunction with the upper end of a connecting rod 33 pivoted to piston guide 32 and moves the push rod 27 up and down between the limits already described due to the action of the relative movement between the machine piston 24 and the piston guide 32. In order to allow for the differences in height, the lost motion cou-

pling 31 is formed as a drag coupling. Naturally the lost motion coupling may be replaced by any similar device.

During the pressing of the sole of the foot wear 21, the upper form and the last pillar 5 with the last are in the position shown in Figure 5 of the drawings. As soon as the last 26 is moved away from the upper form 6 and when the piston 24 sinks, the action of the connecting rod provided between its pin 29 and the stationary piston guide 32 causes the last to move so far in the direction of the toe of the shoe, that due to the return movement of the last pillar 25 a space results under the instep which allows removal from the last (Figure 8). After this the footwear is drawn off the last pillar 25 and the last 26, whereby relatively to the last it is temporarily in the position shown in Figure 10. In this position the space under the instep formed by the sliding of the smoothing last disappears, because in lifting off the shoe sole the upper leather is raised with it and thus comes into the position shown. In setting up work on the last the same operations proceed in the reverse order.

For interchanging, the last 26 is brought into the position shown in Figure 11 in which it can be easily withdrawn from the link 28. As the last can only be brought into the position shown in Figure 11 after the piece of work has been removed, it can only be separated from the last pillar when in the unloaded position. Thus an unintentional removal of the last from the last pillar during pressing, or during the setting up or removal of footwear from the last, is impossible.

In the present invention care is taken to give effective support to the toe of the last by the particular construction of the last and of the part of the last pillar which projects into the toe of the shoe during the smoothing process. With this object it would seem that the toe of the last could be strengthened. In this connection it should be noticed that for a series of smoothing lasts at most only one pair of last pillars is necessary, while in general for each shoe number within a series a special pair of smoothing lasts is necessary. Thus if one wished to make the lasts themselves stronger by using a higher tensile steel or by using a thicker cross section considerably increased costs would result. However, with a last in accordance with the invention the toe of the last pillar 25 which grips underneath the toe of the last is made strongly thus resulting in a powerful base for the toe of the last. In order to allow for this strengthening of the last pillar 25 and to ensure that the last 26 is in the correct place in the pressing position the last 26 is hollowed out on its underside for engaging the strengthened toe of the last pillar, as can be seen in the drawings. This however does not cause a weakening of the effective carrying cross section of the toe of the last; because the last grips over the last carrier like a saddle and in this way is strengthened at the hollowed out portions by the projections which lie at the sides of the last carrier as shown in Figures 7 and 8.

In the construction according to Figures 13 to 15 the piston 24 of the machine is rigidly connected to a last pillar 34. The last pillar is provided with an arcuate guide 35 on which the smoothing last 36 is slidably arranged. The last terminates in a last support 37 which is made integral with it, and which in the position shown in Figure 13 abuts against two fork-

like projections 38. From the cross section in Figure 14 it can be seen that the last 36 or the last support 37 grips round the last pillar 34 which is T shaped in cross section, so as to ensure that the last is correctly guided on the last pillar. The chain dotted lines represent a shoe 39 having a narrow opening. The last 36 is provided with a complete or practically complete heel. A cross pin 40 having a roller 41 mounted thereon, is provided on the last support. As shown in Figure 13 the roller lies in a jaw 42 of a link 43 having an inclined surface 44. The link 43 is formed as a lever pivotally mounted to the pivot pin 45 and has an arm 46 having its end connected to a tension spring 47 the other end of which is attached to a fixed mounting 48. The pivot pin 45 is housed in a projection on a sliding sleeve 49 which is slidably arranged on an upstanding lug 50 which is fixed in the upper end 51 of the piston guide.

The method of operation of the press in accordance with Figures 13 to 15 is as follows:

During the pressing of the sole the last and last pillar are in the position shown in Figure 13. When the piston sinks the last pillar 34 with the last 36 moves downwards, until the sliding sleeve 49 abuts against the fixed projection 51. Then with the further downward movement of the piston 24 the forklike projections 38 move away from the last support 37, whereby the link 43 which is under the influence of the tension spring 47 pushes the last on the arcuate guide 35 finally into the position shown in Figure 15. In this position sufficient space is available under the in-step, to facilitate the removal of the work from the last. In setting work up on the last the same operation takes place in a reverse order.

The exchange of the last 36 is made possible by undoing the link 43, whereupon after separating the last 36 from the push rod the last can be easily withdrawn from the last pillar 34.

I claim:

1. In a sole pressing machine, a last carrying a pillar formed at the upper end to present a toe side and a heel side, a smoothing last, means for guiding the smoothing last with respect to the upper surface of the pillar, means for fixing the last with respect to the pillar in an operative position to arrange the heel portion of the last beyond the heel portion of the pillar and the toe portion of the last beyond the toe portion of the pillar, means for releasing the locking means to permit the last to be moved to an inoperative position whereby the heel portion of the last is substantially aligned with the heel portion of the pillar, the last in operative position supporting an article of footwear for sole pressing purposes, with the leg of such footwear embracing the pillar at an inclination thereto and precluding convenient removal of the article of footwear, the last in the inoperative position causing the leg of the footwear to be changed in position with respect to the pillar to permit convenient removal of the article of footwear, and means for retaining the last in inoperative position.

2. In a sole pressing machine, a smoothing last, a last carrying pillar, the toe side of the pillar projecting toward the toe portion of the last and the heel portion of the last projecting beyond the heel side of the pillar, means for moving the pillar, the last and the article of footwear carried thereby into pressing position, positioning means operated by the pillar moving means and connected to the last to move the last relative to the pillar in the pressing movement of the pillar into

a position with the toe side of the pillar underlying the toe portion of the last and the heel side of the pillar disposed inwardly of the heel portion of the last, said positioning means operating in the reverse movement of the pillar to move the last and footwear carried thereby in a direction to dispose the last and footwear carried thereby for convenient upward movement relative to the pillar.

3. In a sole pressing means, a smoothing last, a last carrying pillar on which the last is movably supported, a piston for moving the last pillar, last and article of footwear supported on the last, a push rod guided on the last pillar and operated relative to the pillar in the movement of the piston, a connection between the push rod and heel portion of the last, said push rod operating through said connection to move the last and footwear carried thereby into predetermined pressing relation to the pillar in the movement of the pillar in one direction and to move the last relative to the pillar to dispose the pillar substantially in alignment with the leg portion of the footwear upon the last in the opposite movement of the pillar.

4. In a sole pressing machine, a last pillar, a smoothing last mounted for movement thereon, a piston operating the last pillar, a guide on the machine in which the piston slides, a push rod slidably guided on the last pillar, an intermediate toggle connection between the push rod and the heel part of the last, and a lost motion coupling connecting the push rod to the piston guide, the push rod operating in the movement of the pillar in the pressing direction to cause the last to assume a predetermined pressing relation to the pillar, said push rod in the opposite movement of the pillar moving the last and the footwear carried thereby to a position to align the last supporting portion of the pillar with the leg of the footwear for convenient removal of the last and footwear.

5. In a sole pressing machine, a last pillar, a last supported on and movable with relation to the pillar, the last supporting position of the pillar providing a toe part to substantially reinforce the toe portion of the last when the latter is in operative position and a heel part disposed inwardly of the heel portion of the last, a piston for moving the pillar, last and footwear carried by the last into pressing position, a piston for operating the pillar, a guide on the machine in which the piston slides, a push rod guided on the pillar and operated relative to the pillar in the movement of the latter, a toggle member connected to the push rod and to the heel part of the last, and a lost motion coupling connecting the push rod to the guide, the toggle connection having a terminal hook to engage a complementary part of the last, whereby to permit separation of the last from the pillar in a predetermined position of the last and in the absence of footwear on the last, the movement of the pillar toward pressing position causing the relative movement of the push rod to set the last in operative position on the pillar, the opposite movement of the pillar serving through the push rod to move the last relative to the pillar to a position to permit removal of the footwear from the last and pillar.

6. In a sole pressing machine, a pillar, a last supported on and movable relative to the pillar, the pillar at the end cooperating with the last having a projecting toe portion and a reduced heel portion, the pressing position of the last relative to the pillar causing the toe portion of

the pillar to reinforce and support the toe portion of the last and the heel portion of the last to be disposed outwardly beyond the reduced heel portion of the pillar, the inoperative position of the last disposing the reduced heel portion of the pillar beneath the heel of the last and the toe portion of the pillar remote from the toe of the last, a piston for moving the pillar, last and article of footwear carried by the last into and from pressing position, a rod connected to the machine and guided on the pillar, said rod being movable relative to the pillar in the operation of the piston, a connection between the rod and last for moving the last in operative position relative to the pillar in the movement of the pillar toward pressing position and for moving the last into inoperative position with respect to the pillar in the movement of the pillar from pressing position, and cooperating means on the pillar and last to compel movement of the last along predetermined lines relative to the pillar.

7. In a sole pressing machine, a last pillar, a last supported on and movable relative to the pillar, the last pillar having a projecting toe portion and a reduced heel portion, the last when in operative pressing position relative to the pillar being disposed with its toe part reinforced and supported by the toe portion of the pillar and its heel part projecting outwardly beyond the heel part of the pillar, a rod connected to the machine and movable relative to the pillar in the operation of the pillar, a piston for operating the pillar, a connection between the rod and last to move the last into operative position on the upward movement of the pillar and into inoperative position upon the downward movement of the pillar, and means for limiting the relative movement between the rod and pillar.

8. In a sole pressing machine, a last pillar, a smoothing last supported by and movable relative to the pillar, the pillar having a projecting toe part and a reduced heel part, the last in operative pressing position on the pillar having its toe portion supported by the toe part of the pillar and its heel portion projecting outwardly beyond the heel part of the pillar, a piston for moving the pillar, last and footwear carried by the last to and from a pressing position, a rod connected to the machine and movable relative to the pillar in the movement of the pillar by the piston, a connection between the rod and last operating to move the last and footwear carried thereby into operative position to the pillar in the movement of the pillar toward pressing position, said rod and connection operating to move the last and footwear carried thereby to an inoperative position in the movement of the pillar from pressing position, complementary means on the last and pillar to guide the last during its movement relative to the pillar, the connection between the rod and last integral with the heel portion of the last, and a projection on the last pillar to be engaged by said connection to support the last when the latter is in pressing relation to the last pillar.

9. In a sole pressing machine, a last pillar, a smoothing last supported by and movable relative

to the pillar, the toe side of the pillar projecting toward the toe portion of the last and the heel portion of the last projecting outwardly beyond the heel side of the pillar, means for operating the pillar, a rod connected to the machine and controlled in the movement of the last to move the last into an operative position with respect to the pillar when the pillar is raised and to move the last to a different position relative to the pillar when the pillar is lowered, the pillar being formed with an arcuate slot and the last being provided with a projection to slide into said slot to compel predetermined movement of the last with respect to the pillar, a connection integral with and depending from the last and removably connected to said rod to compel corresponding movement of the last in the movement of the rod, a sleeve mounted for sliding movement with respect to the pillar and connected to the rod, and a spring to maintain connection between the rod and last projection.

10. In a sole pressing machine, a smoothing last, a last carrying pillar, the toe side of the said last pillar projecting toward the toe portion of the last and the heel portion of the said smoothing last projecting over the heel side of the said pillar, a rod connected to the machine and controlled by the machine to move the last on the raising of the last pillar into the pressing position and to move the last on the lowering of the last pillar towards the toe of the footwear, the last gripping round the last pillar.

11. In a sole pressing machine, a form, a last pillar having a last supporting surface formed with a projecting toe part and a reduced heel part, a last mounted for sliding cooperation with the pillar and designed to receive the footwear, said last having an operative position with the toe portion of the last supported by the toe part of the pillar and the heel portion of the last projecting outwardly beyond the heel part of the pillar and an inoperative position with the toe portion of the last projected further beyond the toe part of the pillar and the heel portion of the last practically overlying the heel part of the pillar, means for moving the pillar, last and footwear carried thereby to and from pressing cooperation with the form, and means controlling the last during the pillar movements to move the last to an operative position in the movement of the pillar toward pressing position and to move the last to an inoperative position during movement of the pillar from pressing position, the movement of the last to an inoperative position disposing the leg part of the footwear on the last for convenient removal from the last pillar.

12. A construction as defined in claim 11, wherein the last pillar and last are formed with complementary means to compel a sliding movement of the last with respect to the pillar.

13. A construction as defined in claim 11, wherein the means for operating the last during pillar movements is limited in effect on the last to insure predetermined last positions in both operative and inoperative relation of the last and pillar.

KURT SANDT.
